(57) **CLAIM**

The ornamental design for an electrically propelled catamaran, as shown and described.

DESCRIPTION

1. Electrically propelled catamaran

1.1 is a front and right side perspective view of an electrically propelled catamaran embodying my new design;

1.2 is a rear and right side perspective view thereof;

1.3 is a front elevation view thereof;

1.4 is a rear elevation view thereof;

1.5 is a right side elevation view thereof;

1.6 is a top plan view thereof; and

1.7 is a front elevation view thereof with raised foils.

Catamaran with electric propulsion motor, equipped with foils.

1 Claim, 7 Drawing Sheets
